UNITED STATES PATENT OFFICE

135,097

DESIGN FOR A COMBINATION MIRROR AND TISSUE DISPENSER

William Lyons, Lynbrook, N. Y., assignor to William Lyons Novelty Co. Inc., New York, N. Y., a corporation of New York

Application July 9, 1942, Serial No. 107,454

Term of patent 7 years

To all whom it may concern:

Be it known that I, William Lyons, a citizen of the United States, resident of Lynbrook, in the county of Nassau, State of New York, have invented a new, original, and ornamental Design for a Combination Mirror and Tissue Dispenser, of which the following is a specification, reference being had to the accompanying drawing, forming part thereof.

In the drawing:

I claim:

The ornamental design for a combination mirror and tissue dispenser, substantially as shown.

WILLIAM LYONS.
